TRAILER NOSE CONSTRUCTION

Harold H. Robinson, Opa Locka, Fla., assignor to
Curtiss Aerocar Company, Inc., Opa Locka,
Fla., a corporation of Florida

Application April 1, 1933. Serial No. 663,947

5 Claims. (Cl. 280—33.1)

This invention relates to the construction of trailer vehicles of the type in which connection is made to the tractor vehicle through a post secured in an elevated prow or nose formed at the forward end of the trailer. A trailer of this type is shown in the patent to Curtiss No. 1,880,844, issued October 4, 1932. The present invention relates more specifically to the manner of securing the prow post in the prow of the trailer and its position with respect to the adjacent truss members.

It is the general object of the invention to provide a trailer, the prow construction of which sustains the concentrated strains of operation in an improved and more efficient manner than in any previously known constructions, and further to provide an arrangement of parts which may be assembled in a manner to secure and preserve in fullest degree the inherent strength of the materials employed. Other and further objects will be apparent from the following description and claims.

In the accompanying drawing which illustrates one embodiment of the invention:

25 Fig. 1 shows in side elevation the assembly of the front end of the body trusses and the nose post;

Fig. 2 is a plan view of the nose post assembly;

Fig. 3 is a sectional view substantially on line 30 3—3 of Fig. 2;

Fig. 4 is a vertical sectional view, on a larger scale, of the nose post at the thrust collar;

Fig. 5 is a sectional view substantially on line 5—5 of Fig. 1;

35 Fig. 6 is a sectional view on a larger scale substantially on line 6—6 of Fig. 1; and

Fig. 7 is a diagram, referred to in the discussion of the distribution of the strains and stresses developed when the vehicle is in operation.

40 It will be understood that the construction is bilaterally symmetrical and that a description of either half applies in detail to the other.

In the drawing reference characters 1, 1' indicate the upper chords of the body trusses, and reference characters 2, 2' the lower chords. The forward ends of the upper chords fit together in a mitered joint 4. The ends of the chords and post 3 are held together by a metal cap member 5 comprising a body portion 6 and top plate 7 welded thereto as at 8. The chords 1 and 1' are secured to the cap member 5 by bolts 9 and the cap member is welded to the post 3 as at 10. The body portion of the cap member is provided with 55 holes 11 to receive anchor bolts 12 for the wire

tension members 13 forming parts of the body trusses.

The lower chords 2, 2' of the trusses are bent upwardly and their forward ends abut the nose post 3. The forward ends of the lower chords are held to post 3 by means of a formed steel plate member 15 having triangular web sides 27 as shown. The chords engage beneath top flanges 16 formed along the upper edge of plate member 15. Short bottom flanges or angle supports 17 engaging beneath the chords are formed by making U-shaped cuts in the web sides of the plate members forming tongues which are bent inwardly and horizontally. The chords are secured between flanges 16 and 17 by means of a plurality of bolts 18. Member 15 at the rear edge of its web sides 27 is also formed with inwardly extending diagonal flanges 20 which serve as stiffening elements which add substantially to the rigidity of the structure.

Wooden reinforcing strut members 21 and 22, held to the plate member by screws 23, further increase the rigidity of the plate and of the structure as a whole. Plate member 15 is formed to closely enclose the front and sides of the nose post 3 and is welded thereto at 25. Plate 15 is provided with upper triangular web portions 26 adjacent post 3, which portions are drilled to receive anchor bolts 28 for wire tension members 29 forming part of the body trusses. The nose portion of the body trusses is completed by rearwardly inclined struts 30, the lower ends of which are secured by bolts 31 to the flange 16 of plate 15. The upper ends of struts 30 are welded as at 32 to extensions 33 formed integral with plates 34. Plates 34 are secured by bolts 36 to the upper chords and to the upper ends of truss posts 37, and are drilled to receive anchor bolts 39 for the upper ends of the wire tension members 29. The lower end of posts 37 are secured to the lower chords 2 by gusset plates 40 secured in the post and chord as by bolts 41, in the manner disclosed in my co-pending application Serial No. 602,754, filed April 2, 1932. The web of gusset plates 40 is drilled to receive anchor bolts 44 for the lower ends of diagonal wire tension members 13. At the posts 37 the body trusses have diverged sufficiently to require cross bracing and this is accomplished by a rectangular cross frame 45 comprising (see Fig. 5) upper and lower cross pieces 46 and side members 47. Cross frame 45 is secured to the adjacent truss members in any suitable manner.

The cross bracing at this point is completed by diagonally positioned wire tension members 38, the upper ends of which are secured by anchor bolts 42 to plates 34 and the lower ends are secured by anchor bolts 43 to the lower chords 2.

Fig. 4 is a vertical sectional view, on a larger scale, of the nose post at the thrust collar;

Fig. 5 is a sectional view substantially on line 5—5 of Fig. 1;

Fig. 6 is a sectional view on a larger scale substantially on line 6—6 of Fig. 1; and

Fig. 7 is a diagram, referred to in the discussion of the distribution of the strains and stresses developed when the vehicle is in operation.

45 It will be understood that the construction is bilaterally symmetrical and that a description of either half applies in detail to the other.

In the drawing reference characters 1, 1' indicate the upper chords of the body trusses, and reference characters 2, 2' the lower chords. The forward ends of the upper chords fit together in a mitered joint 4. The ends of the chords and post 3 are held together by a metal cap member 5 comprising a body portion 6 and top plate 7 welded thereto as at 8. The chords 1 and 1' are secured to the cap member 5 by bolts 9 and the cap member is welded to the post 3 as at 10. The body portion of the cap member is provided with 55 holes 11 to receive anchor bolts 12 for the wire

cured to the inner ends of bolts 41 which secure gusset plates 40. The fastening means at one or both ends of the various wire tension members may include turn buckles 50 for adjusting the 5 tightness of the members.

Member 15 is expanded at its lower end, as best shown in Fig. 4 at 51, to receive extension 52 of thrust collar 53 and the expanded portion 51 is heavily welded to the thrust collar 53 as at 54.

10 The thrust collar in the embodiment shown is formed with an annular recess 55 to receive the locking plate of the fifth wheel coupler arrangement disclosed in co-pending application Serial No. 650,346, filed January 5, 1933, but it will be

15 understood that any other suitable form of locking means may be employed. Nose post 3 is tubular in cross section and is reenforced at its lower end portion with a cylindrical steel insert 56 which extends sufficiently above the thrust collar to

20 assure proper distribution of the strains to member 15. The reinforced portion of the post is extended below the thrust collar as indicated at 57 to form the pin portion of an articulated coupling.

25 Nose post 3 is preferably formed of drawn steel tubing of comparatively light section. This material is well adapted for light, economical, but strong construction but it is a characteristic of this material that when heated excessively, there

30 takes place a molecular rearrangement that destroys the so-called "grain" and leaves the material in a weakened condition. By my arrangement, the strength and manufacturing economies of adequate welding of the parts is secured without

35 weakening the structural parts which would ordinarily result from the use of the high degrees of heat necessary for heavy welding. It is desirable that thrust collar 53 be firmly affixed to nose post 3 and through it to the body of the

40 trailer since the whole weight of the forward end of the trailer is transmitted through the trusses to this member and is concentrated at the lower surface of the collar. Thrust collar 53 is heavily welded to plate 15 at 54 before nose post 3 is inserted.

45 Steel insert 56, made slightly larger in diameter than the bore of nose post 3, is pressed into the bore. The diameter of the bore of collar 53 is slightly less than the outer diameter of post 3 and the collar is expanded by heat to permit the

50 reenforced nose post to be inserted. Upon cooling the collar shrinks to a stressed fit around the nose post 3 thereby holding the latter and the reenforcing insert 56 in heavy compression. It will be seen that the heavy welding at 54 has been accomplished without weakening the nose post 3. The

55 connection of the member 15 to post 3 may be reenforced by lighter welding as shown at the various points 25.

The specific nose structure described, when considered as a whole may be regarded as a prism and is especially adapted to resist heavy concentrated strains which may be suddenly applied in either a vertical or horizontal direction and the direction of application as suddenly reversed.

60 Difficulty has been experienced in the past with the elevated nose type of trailer due to the fact that the forces tending toward failure of the structure are applied at a point out of alignment with the supporting and strengthening members. Moreover the stresses set up in the nose portion and transmitted to the frame are substantially different when the trailer is being drawn forward than when the trailer is being backed or its forward motion retarded by application of the trailer brakes.

Referring to Fig. 7 it will be seen that nose post 3, when stressed by a force acting at its lower end in the direction indicated by the arrow, or in the reverse direction, may constitute a lever of either the first or second orders. It 80 may act as a lever of the first order with lower chord 2 as the fulcrum as is indicated by the letter B and upper chord 1 as the weight, with line BC as the power arm and line AB as the weight arm. It may also act as a lever of the second order with upper chord 1 as the fulcrum and lower chord 2 as the weight, with line AC as the power arm and line BC as the weight arm. Owing to the flexibility inherent in a truss structure, the order of the lever is continually changing from one to the other, and at times both orders of levers are undoubtedly present simultaneously, thereby setting up at the nose structure violent and sudden strains of all kinds including tearing strains. 85

When nose post 3 is acting as a lever of the first order, the point of attachment of lower chord 2 at B is in tension when the direction of the applied force at C is in the direction of the arrow, and distortion of the structure is guarded 90 against by tension wire 29, and in a lesser degree by strut 30. Gyration deformation with point B as a center of gyration is prevented by the triangular shape of formed plate 15. The point of attachment of upper chord 1 at B being 95 in compression tends to move backwardly, and deformation is prevented by tension wire 29, the arched configuration of upper chord 1, and the strut 30. When the direction of the force applied at point C is in the reverse direction from 100 that indicated by the arrow, the stress at point B is compressive and in a rearwardly direction, the strain being taken by lower chord 2 in compression, tension wire 13 in tension and strut 30 in compression, the latter strut tending to act 105 as a moving strut exerting an upward force upon plate 34, which is held against movement by its attachment to rod 37. The stress at A is tensional and the chord is held against movement by tension wire 13, the arched configuration of chord 110 1 and by strut 30.

When nose post 3 is acting as a lever of the second order and the force applied at C is in the direction of the arrow, the point of attachment of upper chord 1 is in compression, and distortion of the structure is prevented by the arch of chord 1, tension wire 29 and strut 30. At point B lower chord 2 is in tension and is held against deformation by tension wire 29, strut 30, and, as the center of gyration is now at point A, by 115 formed plate member 15. When the direction of the force applied at point C is in the reverse direction from that indicated by the arrow, and nose part 3 is acting as a lever of the second order, the stress at point A is tensional and that 120 prevailing at point B compressive; frame distortion being prevented by members 30, 13 and 15 in the same manner as when nose post 3 was acting as a lever of the first order and the direction of the force at C was contrary to that indicated by the arrow. 125

The lateral stiffening at the base of the prism structure of the nose is provided by tension wires 38, cross braces 46 and side members 47 in the conventional manner. 130

What I claim is:

1. In a trailer vehicle of the type wherein the body frame is in the form of trusses, the forward panels of which converge at their forward ends to form a prow, the lower chords of said trusses 135

being bent upwardly and forwardly to elevate the point of attachment to the tractor vehicle; a vertical prow post, forming a common post element of the foremost panels of the body trusses and extending substantially below the forward ends of the lower chords of said trusses, a thrust collar secured to said post adjacent its lower end and forming part of the attaching means for the vehicles and triangular web members secured at their forward portions to said prow post and said collar and respectively secured along their upper edges to the lower chords of the body trusses.

2. In a trailer vehicle of the type wherein the body frame is in the form of trusses, the forward panels of which converge at their forward ends to form a prow, the lower chords of said trusses being bent upwardly and forwardly to elevate the point of attachment to the tractor vehicle; a vertical prow post, forming a common post element of the foremost panels of the body trusses, and extending downwardly substantially below the point where the forward ends of the lower chords of said trusses join said post, a thrust collar secured to said post adjacent its lower end and forming part of the coupling means for the vehicles, and a formed plate fitted around said downwardly extending portion of the post and provided with rearwardly extending web portions, said plate being secured at its bent portion to said post, the rearwardly extending web portions of the plate being secured along their upper edges to the lower chords of said trusses.

edges to the lower.

3. In a trailer vehicle of the type wherein the body frame is in the form of trusses, the forward panels of which converge at their forward ends to form a prow, the lower chords of said trusses being bent upwardly and forwardly to elevate the point of attachment to the tractor vehicle; a vertical prow post, forming a common post element of the foremost panels of the body trusses, and extending downwardly substantially below the point where the forward ends of the lower chords of said trusses join said post, a thrust collar secured to said post adjacent its lower end and forming part of the coupling means for the vehicles, and a formed plate fitted around said downwardly extending portion of the post and provided with rearwardly extending web portions, said collar being shrunk on the post, said plate being heavily welded to the collar and lightly welded to the post, the rearwardly extending web portions of the plate being bolted along their

upper edges to the lower chords of said trusses.

to form a prow, the lower chords of said trusses being bent upwardly and forwardly to elevate the point of attachment to the tractor vehicle; a vertical prow post, forming a common post element of the foremost panels of the body trusses and extending substantially below the forward ends of the lower chords of said trusses, a cap member welded to the upper end of said prow post and bolted to the forward end of the upper chords of the body trusses, said cap member having web portions for attachment of the tension members of said foremost truss panels, a thrust collar secured to said post adjacent its lower end and forming part of the coupling means for the vehicles, and a formed plate fitted around said downwardly extending portion of the post and provided with rearwardly extending web portions, said collar being shrunk on the post, said plate being heavily welded to the collar and lightly welded to the post, the rearwardly extending web portions of the plate being bolted along their upper edges to the lower chords of said trusses.

5. In a trailer vehicle of the type wherein the body frame is in the form of trusses, the forward panels of which converge at their forward ends to form a prow, the lower chords of said trusses being curved upwardly and forwardly to elevate the point of attachment to the tractor vehicle; a vertical prow post constructed of steel tubing and forming a common post element of the foremost panels of the body trusses, a cap member welded to the upper end of said post, the upper chords of the body trusses converging to a mitered joint between the sides of the cap member, bolts securing said chords to the cap member, a plate formed to engage around said post and having rearwardly extending triangular web portions provided with spaced parallel flanges, the lower chord members of the body trusses being engaged between said flanges and converging at said post, bolts securing said lower chords to said flanges and the intermediate portions of the plate, rearwardly inclined struts having their lower ends secured to the rearwardly extending triangular portions of said plate and their upper ends secured at the intersection of the upper chords and the rear posts of the said foremost truss panels, a thrust collar shrunk on the prow post at the lower end of said plate and heavily welded to said plate, said post extending below the thrust collar to form a coupling pin and a solid steel reinforcement press fitted within the lower portion of the nose post and extending above the thrust collar.
